(57) **CLAIM**

The ornamental design for box for holding compact disks, as shown and described.

DESCRIPTION

FIG. 1 is a perspective view of box for holding compact disks showing my design;

FIG. 2 is a top plan view thereof;

FIG. 3 is a bottom plan view thereof;

FIG. 4 is a front elevation view thereof, the rear elevation view being a mirror image thereof; and,

FIG. 5 is a right side elevation view thereof, the left side elevation view thereof being a mirror image.
